UNITED STATES PATENT OFFICE.

WILLIAM GLENN, OF MOUNT VERNON, AND ADELBERT D. HILL, OF CEDAR RAPIDS, IOWA; SAID GLENN ASSIGNOR TO SAID HILL.

COAT AND HAT HANGER.

SPECIFICATION forming part of Letters Patent No. 785,305, dated March 21, 1905.

Application filed March 30, 1903. Renewed February 13, 1905. Serial No. 245,398.

To all whom it may concern:

Be it known that we, WILLIAM GLENN, residing at Mount Vernon, and ADELBERT D. HILL, residing at Cedar Rapids, in the county of 5 Linn and State of Iowa, citizens of the United States, have invented certain new and useful Improvements in Coat and Hat Hangers, of which the following is a specification.

This invention relates to hangers used in 10 hotels, barber-shops, and other public places by means of which hats and coats are securely locked in position and can only be removed by the person holding the key.

The nature of the invention will fully appear from the description and claims following, reference being had to the accompanying drawings, in which—

Figure 1 is a side view of a device embodying our invention with the lock-cap removed. 20 Fig. 2 is a front view of the same. Fig. 3 is a similar view showing a staggered arrangement of hat-lockers. Fig. 4 shows details of the lock. Fig. 5 is a sectional view showing modifications in the construction of the coat-grip. Fig. 6 is one of the spring-retaining washers used therein. Fig. 7 is a section of the hat-grip. Fig. 8 is one of the washers therefor. Fig. 9 is a key, and Fig. 10 a lock-tumbler to register therewith.

30 In the drawings, A denotes a bracket adapted to be secured to cleats B or to a wall. In practice it is usual to connect a number of such brackets in sets to said cleats for convenience in handling and in attachment to the wall. At the top of the brackets so arranged in a row is a rail C, on which rests the middle portion of the hat. Somewhat lower and forward of this rail is another rail, D, to support the lower and outer side of the hat-crown. 35 This rail is secured to upcurved arms A' of the brackets, which leave room above and back of them for the hat-brim. Near the bottom of the bracket is a T-headed coat-hanger E, with room above and about it for adjacent portion of the coat. Below this is the coat-grip, which will be more particularly described hereinafter. Below the outer hat-rail is a lock adapted to secure in closed position

a lever F, whose upper end grips the hat-crown and lower end the coat below the collar. 50

In practice a flat-topped lower hat-rail is preferred. On this rests one side of the hat-crown, and the grip G at the upper end of the curved lever F swings inside the hat-crown and closes down on the material thereof tightly 55 enough to prevent the hat being pulled out, but not so tightly as to mar the hat-crown. The nature of the grip itself is illustrated in Fig. 7.

G' is a cup of soft rubber or the like yielding material furnished with a marginal bead or enlargement G², the rest of the material being comparatively thin and pliable. This cup is held in place on the terminal stem F' of the lever by a metal cup G³ and washers G⁴ and G⁵. The former washer is simply for the purpose of preventing the rubber cup from being twisted or distorted by turning the outer washer G⁵, which is provided with cam-faces G⁶, engaging lateral lugs F² on the stem of 70 the lever, a notch in the cam serving to hold the washer from turning when once in proper position. The back face of the metal cup abuts on a shoulder F³. This construction admits of the parts being very easily and cheaply 75 made and quickly assembled. The parts are strung on the stem in the order shown, the cam-washer last, and all are locked in place by simply turning this washer to the position shown in Fig. 7. By reference to Fig. 8 it 80 will be seen that this washer has lateral notches G⁷ to allow it to slip over the lugs F².

It will be seen that the stem F' terminates a short distance from the rail D, leaving room 85 enough for a thickness of any sort of hat or cap crown material. Provision is made to allow the elastic tip to yield backwardly for the same purpose, and so, also, that fine hats may not be marred by undue pressure; but though held lightly the hat is securely locked 90 in position, since a movement of it in any direction folds one edge of the elastic cup under in the manner indicated by the dotted lines, and the bead wedges the thickness of hat material tightly between the rail and the end of the 95 lever-stem. A somewhat similar grip is pro-

vided for the coat; but in this case practically all the pressure in any case depends upon an attempt to forcibly remove the coat. At the lower end of the lever F is a cup or concave 5 ring F⁴, forming a part of the lever. Opposite this is a convex disk, with ball-and-socket connection with the bracket A. This allows the disk to rock freely a limited distance in any direction. The center of the ball is set 10 forward of the geometric center of the convex disk, and consequently as the disk rocks in any direction one edge moves toward the lever-ring. The convex side of the disk is faced with some soft and slightly-clinging 15 material, such as soft rubber. It is evident now that on any attempt to remove a garment from the hanger above the disk will be drawn to a position to pinch the material tightly between it and the lever-ring. Normally the 20 gravity of the disk brings its upper face in contact with the material of the garment, so that an effort to draw the garment down and out would be instantly resisted; but the action, though not so quick, is the same in 25 any direction, and a handkerchief is held as effectually as a beaver overcoat. In the simpler form shown in Fig. 1 there need be no pressure at all on the garment normally, the parts being somewhat separated even when 30 in holding position. This admits of garments of any thickness being locked against forcible removal, but without the pinching and permanent marring of thick material when subjected to the positive and direct pressure necessary to hold thin material. 35

Back of the disk is a cup-like shield H to prevent access to the disk when the parts are in locking position.

In Fig. 5 is shown a grip adapted for materials varying abnormally in thickness. In this the ball-stem I is provided with a flange I' to take a light spring J, whose office is simply to press the disk up against the garment with just enough tension to cause the 40 grip to act instantly in all directions in case of an attempt to withdraw it. This spring bears against a cupped washer K, through which the stem passes, and on full compression of the light spring the flange I' comes in 45 contact with the washer. Back of the washer is a strong spring L, adapted to give back under hard pressure in case an abnormally thick overcoat or the like intervenes. The rear end of this spring rests against the back 50 (bottom) of the shield-cup, which has a hole in it like that in the washer, Fig. 8, to allow the end of the stem, which has lateral lugs I², to pass through. The cup is also slotted at H', and through these slots extend projections A² of the bracket. These have terminal 55 shoulders A³ to hold the washer K in position and are notched at A⁴ to allow the washer to be put in place. The form of the washer is shown in Fig. 6. A pair of lateral lugs 60 each side straddles the bracket projection be-

tween the terminal lug and the notch, and for convenience in assembling one of each pair of lugs may be longer than the other, so that the washer can only be turned a certain distance, as will be presently explained. 70

The parts are assembled as follows: The shield is first placed in position, then the heavy spring, and next the cupped washer, which is pressed back far enough so that the shorter of its lugs will pass through the notches 75 A⁴. It is then turned in the direction indicated by the arrow until the longer lugs strike the sides of the bracket projections, and the pressure being relieved the washer snaps back into final position, as shown. This of course 80 holds the washer, shield, and spring all in proper place. The ball-stem, with the disk previously attached, is then thrust through the light spring, previously seated, and thence through the washer K, strong spring, and 85 notched hole in the back of the shield, and through a hole A⁵ in the bracket, is turned a quarter-turn or so, thus locking these parts in position.

A simple means of fastening the disk on 90 the ball is shown in Figs. 1 and 5 and consists in snapping an open ring M² in a groove M', formed in the hub of the disk M. This obviates drilling or other machine-work, which in the construction of this device we have 95 sought to eliminate as far as possible.

The central hub F⁵ of the lever F is pivoted in a suitable housing A⁶, forming a part of the bracket. Forward of this is the housing for the lock A⁷, nearly circular. The other half of both housings forms a single cap Z and is fastened to the bracket by a screw (not shown) through the hole A⁸. A stop-shoulder A⁹ limits the closing movement of the lever. The sides of the housings at the top are 100 grooved at A¹⁰ to form guideways for a flat key N, entering a slot at the junction of the housing and the front hat-rail arm. From the front side of the lever-hub springs a wing F⁷, extending nearly to the center of the 105 larger part of the housing. Central to this circle is mounted the lock-tumbler O, the hub of which is partly cut away at O' to allow the wing to pass when in position therefor. From the hub on the other side springs a lug O², 110 and in a tangent line therefrom is a stud O³, both in contact with a spring P when the tumbler is in locking position. The wards of the tumbler are in the nature of diverse-shaped projections from the periphery and 115 register with similar holes in the key in the same manner as do a rack and pinion. A stop-stud A¹¹ limits the movement of the tumbler in the final locking position. The locking position first above referred to is that 120 shown in Fig. 4 and is a spring-lock independent of the action of the key. It will be seen that in this position of the tumbler the lever-wing may sweep downwardly, rocking the tumbler a little to the right. As soon as 125 130

its upper angle passes the lower angle of the tumbler, however, the spring, acting on the stud O^3 , moves it to the position shown. The lever is now locked, and the withdrawal of 5 the key rocks the tumbler back without otherwise affecting its locked position. To unlock, it is only necessary to push the key in as far as it will go, when the lock-lever moves out of locking position by gravity. The key remains in the lock and cannot be withdrawn except by returning the lever to the locking 10 position. The user of the locker is thus assured that his garments are secure whenever it is possible for him to withdraw the key.

15 Attention is directed to the fact that the coat-grip is below the hanger-hook therefor and independent of it. This makes it possible to provide a grip which does not press or pinch the garment except on an attempt to 20 forcibly remove it, as above set forth.

The device is adapted for either coats alone, hats alone, or both. In case of the latter use alternate coat-levers may be lengthened, as 25 shown in Fig. 3, so that coats may hang in a single line, or practically so, and hats may be in staggered positions with a view to occupying less space laterally. For coats alone all of the apparatus above the lock may be dispensed with. For hats alone all below the 30 lock except enough of the lock-lever to form a hand-lever.

Having thus described our invention, what we claim as new, and desire to secure by Letters Patent, is—

35 1. In a locker, the combination with lever-support, hat-supporting rails and locking mechanism, substantially as described, of a pivoted lock-lever terminating near the lower rail, when in locked position, and a tip therefor of flexible material adapted to retain the hat without pinching it, but to fold under the end of the lever and grip the hat on an attempt to remove the same.

40 2. In a locker, the combination with lever-support, hat-supporting rails and locking mechanism, substantially as described, of a pivoted lever terminating near the lower rail, when in locked position, and provided with an annular tip of flexible material adapted to 45 fold between the lever end and the hat and grip the same, on an attempt to forcibly remove it.

50 3. In a locker, the combination with lever-support, hat-supporting rails and locking mechanism, substantially as described, of a pivoted lock-lever terminating in final position near the lower hat-rail, a cup-like tip therefor of flexible material, and with a bead or enlargement adapted to wedge between the 55 end of the lever and the hat on an attempt to remove the latter.

60 4. In a locker, the combination with suitable lever-support, hat-supports and locking mechanism, of a pivoted lock-lever provided

with a cup-like flexible tip mounted near its 65 end, and an inclosing metal case therefor, terminating a little short of the edge of the tip.

5. In a coat-hanger, the combination with a hanger-hook and locking mechanism, of a lock-lever adapted to engage one side of the 70 coat, a gripper set opposite thereto and adapted to rock on a fixed center of motion universally, and a facing of yielding and somewhat clinging material on its coatward face, substantially as and for the purpose set forth. 75

6. In a coat-locker, the combination with suitable locking mechanism, of a lock-lever terminating in an annular gripping-face, and a convex-faced disk mounted by ball-and-socket joint opposite thereto, and adapted to 80 grip material between them when moved in any direction.

7. In a coat-locker, the combination with suitable locking mechanism and coat-support, 85 of a gripper held to normal position by a strong spring, a lock-lever coacting therewith to grip the coat if tampered with, but not otherwise, and a connection of the gripper with said spring, whereby abnormally thick material may be admitted, as specified. 90

8. In a coat-locker, the combination of a hanger, a lock-lever, and suitable locking mechanism, and a gripper pivotally mounted to engage the opposite side of the material and pinch it tightly against the lever, if tampered with, a movable support for said gripper, and a light spring to hold the gripper with soft contact against the material and secure quick gripping contact. 95

9. In a coat-locker, the combination of a 100 hanger, a lock-lever, and suitable locking mechanism, and a gripper pivoted to coat with the lever if the coat is tampered with, a movable support for the gripper, a strong spring adapted to yield under extraordinary 105 pressure, a spring adapted to hold the gripper lightly in contact with the interposed material, and independent connections of said spring with the gripper, whereby the action of either is not affected by the other. 110

10. In a coat-hanger, the combination with a lock-lever, of a gripper comprising a gripping-disk mounted by ball and socket on a movable spindle, a flange on said spindle, a light spring back of the flange, a sliding washer mounted loosely on the spindle, a support for said spindle and washer adapted to allow the washer to slide a limited distance, and a strong spring mounted between the washer and said support. 115 120

In testimony whereof we affix our signatures in presence of two witnesses.
